CLASP

John E. Freysinger, New Britain, Conn., assignor to North & Judd Manufacturing Company, New Britain, Conn., a corporation of Connecticut

Application December 15, 1939, Serial No. 309,382

5 Claims. (Cl. 24—248)

This invention relates to blanket clasps or buckles of the type used in baby cribs and bassinets. Such clasps are anchored to the crib and when so anchored are adapted to grip and hold blankets and other covering material in a desired position over an infant and to thereby prevent the child from moving same to an undesirable or dangerous position.

Heretofore a variety of anchoring means have been used to accomplish the above indicated purpose. It is a requirement of these various anchoring means that they lack any potentially dangerous parts and that they be capable of securely holding either a single thickness or several thicknesses of covering as may be required to properly protect the child.

It is therefore, the object of the present invention to provide an improved inexpensive clasp, without dangerous teeth or points, sufficiently flexible in its mode of operation to satisfy these requirements.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawing.

Figure 1 is a plan view looking down from the top of the blanket clasp;

Fig. 2 is a plan view looking up from the underside of the clasp;

Fig. 3 is a cross-sectional view of the clasp taken along line 3—3 of Fig. 2;

Fig. 4 is a profile of the clasp showing closed and open positions;

Fig. 5 is a cross-sectional view taken along line 5—5 of Fig. 2; and

Fig. 6 is a plan view of the clasp showing the anchoring means and the blanket covering properly positioned.

Referring to the drawing the invention comprises generally a clasp 10 including a base member 12 having fixed thereon a gripping member 14, and a pivotally mounted clamping member 16 having pivotally mounted thereon a second gripping member 18, the gripping members 14 and 18 being adapted to cooperatively interlock for holding therebetween one or more thicknesses of blanketing.

In the embodiment illustrated, the base member 12 comprises a substantially rectangular metal plate 13 having a rearwardly extending

tongue portion 20 slightly offset beneath the plane thereof and suitably pierced to provide an anchor opening 22. The opening 22 is adapted to receive a strap or tape 24 whereby the base member may be suitably secured to a portion of a baby's crib, as for example, the rod 26. Each of the four corners of the plate 13 of the base member is further provided with a gripping lug 28 adapted to be pressed downwardly and inwardly over the supporting end 30 of the gripping member 14 to rigidly secure same to the base member.

More specifically, the gripping member 14 is a length of spring steel wire bent to define a U-shaped loop and provide spaced apart side arms 15 and 17 connected at their outer ends by a transverse cross bar 19. The side arms 15 and 17 include parallel supporting inner end portions 30 securely positioned beneath the securing tabs 28, the inner ends of the end portion 30 having inwardly projecting offsets 32 and the outer ends inwardly projecting offsets 34, the offsets functioning spaced apart shoulders preventing transverse movement of the end portion 30 relative to the securing lugs 28 and thus holding the loop member in a rigid preset position on the base member 12. Outwardly of the offsets 34 and at right angles thereto the side arms each include short parallel portions 36 connecting into complementary arcs 38. The portions of the side arms extending from the outer terminus of the arcs 38 are then bent upwardly to provide substantially vertically extending spaced apart end portions 40 and 41, terminating above the plane of the base member 12 and interconnected by the transverse cross bar 19.

With this construction there is thus provided a spring steel gripping member of loop form having a wide central portion defined by the complementary arcs 38 converging into a narrow end portion defined by the vertically extending portions 40 and 41 and the interconnecting cross bar 19. Due to the positioning of the cross bar above the plane of the base member there is provided in effect a U-shaped hook eye 43 adapted to receive a hook provided on the complementary gripping member 18 as hereinafter becomes apparent.

There is further mounted on the base 12 a clamping member 16 comprising a substantially rectangular plate 21 provided with side flanges 44 extending downwardly therefrom to either side of and below the base member 12. Extending forwardly from each flange is a supporting arm 45, the forwards of which have oppositely

disposed aligned openings 46 cut therein to pivotally mount the clamp on oppositely disposed lugs 48 extending outwardly from either side of the base member 12. When so mounted the clamping member 16 is adapted to lie in clamping position when the plate 21 thereof is pivoted into contacting surface engagement with the tongue 20 of the base member 12. For convenient manipulation the plate 21 may include a lip 50 which extends rearwardly therefrom and is flared upwardly and out of the plate thereof to permit it to be readily gripped.

As previously indicated, the clamping member 16 provides a support for the cooperating gripping member 18, and more specifically, the gripping member 18 comprises, like member 12, a substantially U-shaped loop member formed from a length of spring steel wire to provide spaced apart side arms 51 and 53 interconnected at their outer ends by a transverse cross bar 55. To mount the gripping member 18 on the clamping member 14 the inner ends of the side arms are turned inwardly to provide lugs or pintles 54 journaled in oppositely disposed openings 56 provided in the downwardly extending flanges 44 of the clamping member 14. The pivotal connection between the gripping member 18 and the clamping member 14 is rearwardly of and arranged in a plane below the pivotal connection between the clamping member 14 and the base member 12, the reasons for this being herein-after apparent.

In order to have the gripping member 18 properly positioned relative to the clamping member 14 the side arms 51 and 53 thereof extend upwardly and substantially parallel to one another from the pivotal connection on the base member 14 and then diverge towards one another to provide parallel portions 58 having a transverse spacing therebetween which is less than the transverse spacing between the arc portion 38 of the gripping member 14. Thus the narrow central portion of the gripping member 18 will overlie the wider central portion of the gripping member 14 and limit the downward pivotal movement thereof to the plane of the lower gripping member. Forwardly of the parallel portions 58 the side arms again diverge outwardly and their outer ends are interconnected by a cross bar 55. The divergency of the outer ends is such that the transverse spacing therebetween is greater than the outer ends of the side arms of the gripping member 14, enabling the outer end of the gripping member 14 to be received through and spaced between the side arms and cross bar of the gripping member 18. In order to interlock the gripping members together the cross bar 55 of the gripping member 18 has a centrally positioned rearwardly offset portion which, in effect, constitutes a hook 62 adapted to be received between the vertical end portions 40 and 41 of the side arms of the gripping member 14 and lie beneath the transverse cross bar 19 thereof, as clearly indicated in the drawing.

With the clasp so constructed, it will be seen that upon pivoting the clamping member 16 in a counterclockwise direction a toggle action is set up resulting in the raising of the pivoted end of the gripping member 18 above the plane of the gripping member 14 and simultaneously moving the hook 62 thereof forwardly and out of the hook eye 43 of the gripping member 14. Upon clearing the hook eye the member 18 may then be lifted as indicated by dotted lines in

Fig. 4, whereupon a blanket may be inserted between the gripping members. Thereafter the gripping member 18 is again pivoted to lower its forward end and to permit the hook eye of the member 14 to pass therethrough. Thereafter the clamping member 16 is pivoted to its closed position to securely grip the blanket as seen in Fig. 5 and inasmuch as the pivot of the gripping member 18 is below the pivot of the clamping member, a positive locking will result.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A clasp comprising a base member having a portion securable to a flexible anchor strap, a gripping member mounted on the base member, said gripping member comprising a loop having a reduced outer end, a clamping member pivotally mounted on the base member, a second gripping member pivotally mounted on the clamping member and comprising a loop having an enlarged outer end through which the reduced end of the first gripping member may pass and cooperating means carried by the outer ends of said gripping members for interlocking same when the end of one gripping member is positioned within the other.

2. A clasp comprising a base member, a clamping member pivotally carried thereby, a gripping member comprising a loop and a wide central portion and a narrow end portion raised above the plane of the side central portion and a second gripping member pivotally carried by the clamping member and comprising a loop having a central portion narrower than the central portion of the said first gripping member and an end portion wider than the end portion of said first gripping member, the end portion of said second gripping member being releasably interlockable with the end portion of said first gripping member when the clamping member is in a locking position.

3. A clasp comprising a base member and a clamping member pivotally mounted on the base member, a gripping member carried by the base member and comprising a pair of spaced apart side arms having their inner ends secured to the base member and their outer ends curved inwardly and terminating above the plane of the base member and interconnected by a transverse cross bar, a second gripping member carried by said clamping member and comprising a pair of spaced side arms having their inner ends pivotally mounted to said clamping member, said side arms then converging towards one another to a space less than the spacing between the side arms of the first gripping member and then diverging from one another so that their outer ends have a greater spacing than the outer ends of said first gripping member and a transverse cross bar interconnecting the outer ends of the side arms of said gripping member, said cross bar having a rearwardly extending portion under-

60
65
70

lying the cross bar of said first gripping member when the clasp is in closed position.

4. A clasp of the character described including a rigid gripping member, a clamping member having a pivot support fixed relative to said gripping member and manually pivotable between a forward and a rearward position, a second gripping member having a second pivot mounting located outwardly on the clamping member and movable with the clamping member to either side of the first gripping member, inter-engaging means on the outer ends of said gripping members, said second gripping member being free to locate entirely to one side of the first gripping member when the clasp is in the open position and the clamping member is in the forward position, and having its outer end and piv-

ot mounting secured on the other side of the first gripping member when the clasp is closed and the clamping member is in the rearward position.

5. A clasp including a rigid gripping member, a clamp pivotally mounted relative thereto and manually movable to a forward and a rearward position, a second gripping member pivotally mounted on the clamping member and extending forwardly of the first gripping member when the clamp is in the forward position, said second gripping member interlocking and tensioning with the first gripping member as the clamp is drawn rearwardly to a positive locking position.

JOHN B. FREYSINGER.
